UNITED STATES PATENT OFFICE.

WILHELM HOPF, OF KIEL, GERMANY, ASSIGNOR TO FRIED. KRUPP GERMANIAWERFT AKTIENGESELLSCHAFT, OF KIEL-GAARDEN, GERMANY.

WATER-TUBE BOILER.

Application filed September 25, 1925, Serial No. 58,670, and in Germany January 2, 1925.

In water tube boilers consisting of one or more upper and lower drums and nests of tubes connecting the same, the guiding of the hot gases is mostly performed by uniting 5 some rows of tubes into a gas-tight tube-wall. In this respect, tube-walls lying at the outer walls of the boiler mainly serve the purpose of restricting to the lowest possible degree the loss of heat to the outside.

10 The invention relates to water tube boilers of the kind stated and has more particular reference to a construction in which a superheater is inserted in the first nest of tubes in such a manner that a superheater tube each 15 alternates with a row of water tubes lying transversely of the boiler drums. In order to allow of the superheater to be inserted in this manner, one has hitherto omitted the corresponding tubes of the tube-wall at the 20 places where the superheater tubes pass through the outer tight tube-wall into the nest of water tubes. However, the tight wall is thereby interrupted at those places on the entire height of the boiler so that the loss 25 of heat to the outside is considerably increased.

The invention has for its object to avoid this drawback. This is attained according to the invention by bending at the places 30 where the superheater tubes penetrate into the nest of tubes, the corresponding tubes of the outer tight tube-wall for such a length behind the neighbouring tubes that openings 35 are produced through which the superheater tubes can be introduced into the nest of water tubes.

Two embodiments of the subject-matter of the invention are illustrated in the accompanying drawing in which:

40 Fig. 1 is a section, transverse of the drum axis, through a boiler constructed in accordance with the invention.

Fig. 2 is a similar section of a boiler provided with another form of superheater,

45 Fig. 3 is a view of the front tight tube wall corresponding to Fig. 1,

Fig. 4 is a section through the tight tube wall along the line 4-4 of Fig. 3,

Fig. 5 is a section through the tube-wall in

the range of the superheater along the line 50 5-5 of Fig. 3.

The embodiment according to Fig. 1 will be described first.

The upper drum A is connected with the lower drum B by a nest of water tubes C. 55 The outer rows of tubes c^1, c^2 are arranged close together for the purpose of forming gas-tight tube-walls. The path of the gases of combustion is indicated by an arrow. Arranged in the nest of tubes is a superheater 60 D consisting of zig-zag tubes which open into collectors d^1 outside the boiler. A pipe E connects the superheater with the steam space of the upper drum A. The superheater is arranged so that a superheater tube 65 each alternates with a row of water tubes lying transversely of the boiler drums. At the places where the superheating tubes penetrate into the nest of water tubes, the corresponding water tubes c^2 of the outer 70 tight tube-wall c^1, c^2 are bent behind the adjacent tubes c^1 (Figs. 1, 3 and 5) in such a manner that openings are produced through which the superheater tubes can be inserted into the nest of water tubes, while 75 the tube-wall is tightly closed above and below those places.

In the arrangement according to Fig. 2 the superheater D consists of several U-shaped tubes which are connected to collectors d^1 80 and bent so that they extend upwardly into the nest of water tubes. In this case, the superheater tubes are passed through the tight tube-wall rather close to the lower drum B. Therefore the bent-off pipes c^2 85 are not bent back into the plane of the tight wall below the superheater but they are guided down in their bent-off position and fastened in the lower drum.

Claims:

1. A water tube boiler comprising an upper and a lower drum, a nest of water tubes connecting said drums with each other, said nest including inner tubes and an outer tube-wall consisting of tubes in close contact 95 along a portion of their length for guiding the heating gases, some of the tubes of the tube-wall being bent back behind adjacent

tubes of the tube-wall to form openings in said tube-wall, and a superheater comprising tubes inserted through said openings and extending between the inner tubes of said nest.

2. A water tube boiler of the kind set forth in claim 1, in which the tubes of the superheater penetrate the outer tube-wall in

proximity to the lower drum and in which the bent-back tubes of the said wall are extended down to the lower drum in their bent-back position. 10

The foregoing specification signed at Hamburg, Germany, this 29th day of August, 1925.

WILHELM HOPF.
